US00D792962S

(12) **United States Design Patent** (10) Patent No.: **US D792,962 S**
(45) Date of Patent: **** Jul. 25, 2017**

(54) **CATCH BASIN COVER**(71) Applicant: **Draingarde Inc.**, Collingwood (CA)(72) Inventor: **Jason Honeyball**, Collingwood (CA)(73) Assignee: **DRAINGARDE INC.**, Collingwood (CA)(**) Term: **15 Years**(21) Appl. No.: **29/576,292**(22) Filed: **Sep. 1, 2016****Related U.S. Application Data**

(62) Division of application No. 29/510,492, filed on Nov. 28, 2014, now Pat. No. Des. 768,843.

(51) LOC (10) Cl. **23-04**

(52) U.S. Cl.

USPC ..... **D23/386**(58) **Field of Classification Search**

USPC ..... D23/323, 328, 333, 335, 336, 337, 341, D23/352, 357, 370, 385, 386, 397, 399, D23/400, 406, 411, 413, 499; D13/182 CPC B64C 11/04; B64C 11/16; B64C 11/18; B64C 11/20; B64C 2001/009; F03D 3/062; F03D 11/04; F04D 19/002; F04D 25/068; F04D 25/088; F04D 19/00; F24F 1/0018; B64D 13/02; E04C 2/427; E06B 3/5892; B24B 37/04; B01D 46/00

See application file for complete search history.

FIG. 10 is a left side view of the catch basin cover shown in FIG. 8;

FIG. 11 is a front view of the catch basin cover shown in FIG. 8;

FIG. 12 is a right side view of the catch basin cover shown in FIG. 8;

FIG. 13 is a rear view of the catch basin cover shown in FIG. 8;

FIG. 14 is a plan view of the catch basin cover shown in FIG. 8; and,

FIG. 15 is a bottom view of the catch basin cover shown in FIG. 8.
